METHOD OF MAKING REINFORCED PADDING SUPPORTS

Frank B. Williams and Harold E. Williams,
Carthage, Mo.

Application August 5, 1940, Serial No. 351,460

3 Claims. (Cl. 140—107)

Our invention relates to improvements in methods of making reinforced padding supports.

It relates particularly to the making padding supports which are adapted for disposal upon the ends of coil springs, used in upholstered seats, backs and the like, the supports serving to prevent pads or padding covering the springs from being forced into or between the springs.

One of the objects of our invention is the provision of a novel method of making a padding support of the kind described in which reinforcing members, as wires, are woven into a fabric strip, as one made of hemp, sisal, jute, or cotton, such as burlap, while the strip is being woven.

A further object of our invention provides novel means for establishing holding engagement of the members, as wires, so woven, with pliable members transverse thereto, as strips of flexible or cord-like material.

A further object of our invention is the provision of a novel method of making a reinforced padding support, which is simple and economical in its performance.

The novel features of our invention are herein-after fully described and claimed.

In the accompanying drawings illustrative of our improved method,

Fig. 1 is a plan view of a partly completed padding support made in accordance with one form of our improved method, the reinforcing members being woof wires having eyes at their ends.

Fig. 2 is a view similar to Fig. 1, in which the end eyes are partly open for admitting the transverse pliable members.

Fig. 3 is a plan view, similar to Fig. 1, showing the pliable transverse members extending through the end eyes.

Fig. 4 is a cross section on the line 4—4 of Fig. 3.

Fig. 5 is a view similar to Fig. 4, showing the eyes partly open, prior to their being closed, as in Fig. 4.

Fig. 6 is a plan view, partly broken away, showing a partly completed reinforced fabric strip, made in accordance with a modification of our improved method, in which the reinforcing members or wires are warp members of the strip.

Fig. 7 is a plan view of a partly completed padding support, severed from a strip corresponding to that shown in Fig. 6, showing the ends of the warp wires formed into partly open eyes.

Fig. 8 is a plan view of a completed reinforced padding support made in accordance with the modified form of our improved method, the pli-

able cord-like members being shown extended through the closed eyes of the reinforcing wires.

Similar characters of reference designate similar parts in the different views.

Referring to Figs. 1 to 5, 1 designates the warp and 2 the woof strands of a fabric strip, which for clearness purposes is shown with a very coarse mesh. The strip may be burlap, or other material, composed of hemp, sisal, jute or cotton strands, as desired.

During the weaving of the fabric strip woof reinforcing members, such as metal wires 3, are woven in the strip at spaced intervals.

In Fig. 1 the ends of the wires 3 are shown provided with eyes 4. In Fig. 2 the ends of the wires are shown with partly open eyes 4'. The eyes 4 and 4' are herein termed lateral offset portions.

When a desired length of the reinforced strip 20 has been woven, it is severed transversely across the warp strands 1 into portions of desired lengths for padding supports.

Two parallel pliable members 5, as cords, are disposed respectively in the closed eyes 4 by 25 threading through, or by being shifted laterally into the partly open eyes 4'. In the latter case the partly closed eyes 4' are closed by crimping, so as to tightly clamp the members 5, if such clamping is desired. The closed eyes 4 may also 30 be crimped into tight engagement with the members 5. Or, if desired, the eyes may have holding engagement with the pliable members 5 by simply encircling them, which will hold the wires 3 from lengthwise movement.

35 Our invention provides also the employment of reinforcing woof wires having no eyes when woven in the strip, the ends of the wires after the weaving of the strip has been completed being formed respectively around the pliable members 5 into holding engagement therewith.

40 In the form shown in Figs. 6, 7 and 8, the reinforcing wires 6 are warp wires which are woven into the strip as the strip of fabric 1—2 is being woven.

45 The reinforced strip, shown in Fig. 6 is severed transversely through the warp strands 1 and the wires 6 into portions of desired lengths for padding supports.

The opposite ends of the wires 6 are then fastened into holding engagement with the pliable members 5, by forming the end portions of the wires around the members 5, or, as shown in Fig. 7 the ends of the wires 6 may be formed into partly open eyes 4' which receive therein laterally the members 5, after which the eyes are

closed to hold the members 5 loosely or, if desired, the eyes are crimped into tight nonslip engagement with the members 5.

In Fig. 1 is shown a padding support which eliminates the pliable members 5. In this form, the eyes 4 serve a double function, that of providing lateral offset portions which prevent the reinforcing members 3 from lengthwise movement, and that of preventing the ends of the members from puncturing upholstering material with which they may contact.

In the form of padding support shown in Fig. 7, the partly open eyes 4' on the ends of the warp members 6, may also serve the same two functions. Or the pliable members 5 may be eliminated in the form shown in Fig. 8, and the members 6 with the closed eyes 4 used alone for reinforcing purposes.

With our improved method, the reinforcement is incorporated into the fabric strip during the manufacture of the latter, thus avoiding subsequent extra handling and work, and effecting a saving in the manufacture of the reinforced padding supports.

Other modifications of our invention, within the scope of the appended claims, may be made without departing from the spirit of our invention.

What we claim is:

1. The method of making a reinforced padding

30

support, consisting in weaving woof wires into a fabric strip as the strip is being woven, by interweaving transversely between the warp strands at spaced apart intervals between the woof strands, and effecting clamping holding engagement of said woof wires with two pliable members transverse thereto and separate from said woof and warp strands.

2. The method of making a reinforced padding support, consisting in weaving woof wires into a fabric strip as the strip is being woven, by interweaving transversely between the warp strands at spaced apart intervals between the woof strands, and forming the end portions of each of said wires around and into holding engagement with two pliable members transverse thereto and separate from said woof and warp strands.

3. The method of making a reinforced padding support consisting in weaving woof wires into a fabric strip as the strip is being woven, by interweaving transversely between the warp strands at spaced apart intervals between the woof strands, and forming the end portions of each of said woof wires around and into clamping holding engagement with two compressible pliable members transverse thereto and separate from said woof and warp strands.
